UNITED STATES PATENT OFFICE.

JAMES THOMAS MORTON, OF KANSAS CITY, MISSOURI, ASSIGNOR TO J. T. MORTON GUM CO., OF KANSAS CITY, MISSOURI, A CORPORATION OF MISSOURI.

DESIGN FOR CANDY.

51,707.

Specification for Design.

Patented Jan. 22, 1918.

Application filed July 10, 1917. Serial No. 179,757. Term of patent 3½ years.

To all whom it may concern:

Be it known that I, JAMES THOMAS MORTON, citizen of the United States, residing at Kansas City, in the county of Jackson and State of Missouri, have invented a new, original, and ornamental Design for Candy, as shown in the accompanying drawing.

Figure 1 is a view of the candy in elevation seen from either side, both sides being identical.

Fig. 2 is a diametrical sectional view showing the surface conformation.

I claim:

The ornamental design for candy as shown.

JAMES THOMAS MORTON.

Witnesses:

W. H. SLOAN,
H. E. WINTERTON.
